DISPLAY APPARATUS

Otto Janzen, Berlin Hermsdorf, Germany, assignor of one-third to Pollopas Patents Ltd., London, England, a company of Great Britain, and two-thirds to Walter Agulnik, Berlin-Dahlem, Germany

Application December 23, 1935, Serial No. 55,821
In Germany December 24, 1934

3 Claims. (Cl. 40—133)

For the illumination of display apparatus such as firms' signs, shop-window advertisements, etc., use is frequently made of luminous letters. These letters are usually shown in light of a single colour. By the provision of flowing light, even more colour effects have recently been obtained, the movement of a coloured disc or of coloured rods being visible in the glass letters or signs forming the display surface.

An object of the invention is to provide a device for illuminated advertising with flowing light by arranging a light, refracting surface between the light source and the display surface.

In carrying the invention into effect in one form there is provided display apparatus comprising a display surface constituted wholly or in part by one or more lens- or prism-shaped translucent bodies and comprising a further translucent refracting body which has an irregular surface and is arranged between a light source and the display surface and is movable transversely to the rays from the light source directed toward the display surface to give the appearance of flowing light in the translucent parts of the display surface.

In the accompanying drawing Figure 1 shows in sectional elevation an embodiment of the invention; Figure 2 shows an end view from the left of the apparatus shown in Figure 1; Figure 3 shows a multi-coloured translucent disc with its support, which parts appear also in Figure 1; Figure 4 shows a lamp assembly and supporting disc which appear also in Figure 1; Figure 5 shows in sectional elevation another embodiment of the invention, somewhat simpler than the apparatus shown in Figure 1; and Figure 6 shows diagrammatically a sectional view of the apparatus of Figure 1.

In the embodiment shown in the Figures 1 to 4 of the drawings the casing 1 is suitable for suspension in a shop-window or in the open. In the latter case, it may also easily be made watertight and, as indicated, be suspended from cables or the like. The casing 1 is closed by a wooden, sheet-metal or other wall 2 which does not admit, or only partly admits, light, and which carries the letters or signs 3 forming the display surface. Openings 4 corresponding to the shape of these letters or signs are provided in the wall 2 behind the letters for their illumination from the interior.

In the interior of the casing 1, a translucent body 5 is provided, of which the surface α facing the wall 2 is made uneven. This body 5 may preferably consist of an ordinary ornamental glass

disc, the surface of which is hammered, fluted, ornamented in the form of ice flowers, or made uneven in some other manner. There is attached to the body 5 a coloured disc of one or more colours which may be an independent unit or formed as a coating of translucent coloured varnish or the like on the body 5. The body 5 is mounted together with the coloured disc 6 in rollers 7, the lower roller of which preferably serves at the same time to impart to the body 5 a rotation in its own plane, which is produced, for instance, by an electric motor 8 through a reduction gear 9. If desired, the illuminating arrangement 10 may also be set into rotation by the same gear. It is quite possible to rotate the body 5 with the coloured disc 6 in one direction and to rotate the illuminating arrangement 10 in the other direction and/or to impart different speeds to them. Likewise, it is possible to mount the body 5 and the coloured disc 6 in different rollers 11 and move them in different directions and, if desired, at different speeds. The coloured disc 6 alone or together with the body 5 may, if desired, alternatively be axially driven. Just as it is possible to obtain a variation of the apparent speed 15 of the light flow by varying the speeds of rotation of the individual parts, such variation may also be obtained by varying the angles of incidence and emanation of the light, which can be achieved by varying the distances between the body 5 and 20 the display surface or the light source. To this end, the bearings for the body 5 and the coloured disc 6 may be arranged so as to be displaceable along the path of the rays. The letters and signs to be illuminated consist of colourless glass or the 25 like of prism or lens-shaped cross-section. By lens-shaped it is meant that one of the surfaces is, or both are, continuously curved. Preferably the letters and signs are round glass rods. The driving motor 8 may, of course, be arranged at 30 any other place in the device. It may even be arranged outside the casing 1 and may be provided with a regulable speed of rotation. When arranging several separate devices for illuminated advertising, for example in a row, these devices 35 may be commonly driven by a motor.

As is seen in Figure 3, the coloured disc 6, which is rotatably mounted between the rollers 7, may consist for instance, of three concentric colour zones, each of which consists of a plurality 40 of surfaces of different colours.

Figure 4 shows an arrangement of the light source 10, which consists of a central incandescent lamp and four incandescent lamps uniformly distributed over the rotating surface. Of course, 45

the light source must be suited to the light requirements of the display surface.

Figure 5 illustrates a device for illuminated advertising which merely differs from that shown in Figures 1 to 4, in that only one central light source is provided, this being sufficient for smaller display surfaces.

Band-like devices may be used instead of one or more rotating discs. This modification is not fully illustrated but, for instance, can readily be performed by arranging the body 5 and the coloured surface 6 in the fashion of a Venetian blind, while suitably modifying the drive for band-like movement. Strip-like display surfaces may also be employed.

Figure 6 diagrammatically illustrates the action of the device. The light emanating from the light source 10 passes through the coloured disc 6 and to the light-refracting surface α of the disc 5, from which it passes with its refractions into the body of the luminous letter 3, completely illuminates the latter and is reproduced over its entire surface. If the disc 5 is moved transversely to the rays in the direction of the arrow, the apparent motion in the same direction of the light leaving the surface α is converted into an apparent circular movement in the light leaving the rod-shaped illuminated letter 3, so that the impression is created of light flowing in the direction of the arrow indicated therein, which impression can be varied from moving light zones to the apparent flow of a luminous liquid according to the degree and nature of the unevenness of the surface α . If the coloured disc 6 is moved simultaneously with the disc 5, the flowing light in the luminous characters 3 is coloured in accordance with the part of the coloured disc which cuts the light beam at the particular time, or is blended by the refraction, whereby a luminous representation is obtained which captivates the spectator by the magnificence of its animated colour. Owing, to the continuous movement of the light-refracting ornamental disc, an apparent transplantation of its ornamentation into the luminous letters or pictorial

characters is accomplished by the simplest means.

I claim:

1. Display apparatus comprising a light source, a display surface having signs thereon, said surface being constituted at least in part by refracting translucent bodies, and a disc of translucent material having an irregular refracting face, said disc being arranged between said light source and said surface and means for rotating said disc about an axis passing approximately through said light source and through the middle of said surface and a disc of multi-colored translucent material rotatable about the same axis as said irregular faced disc.

2. Display apparatus comprising a casing, a source of light within the same, a display surface allowing light to pass through the same at least in part, a rotatable disc of solid material allowing light to pass therethrough, said disc being substantially parallel to said surface, a motor within said casing and means associated therewith for rotating said disc, the face of said disc adjacent to said surface being uneven to provide irregular refraction and the opposite face being relatively smooth, and a multi-colored rotatable disc allowing light to pass therethrough interposed between said source of light and said first mentioned disc.

3. Display apparatus comprising a casing, a source of light within the same, a display surface allowing light to pass through the same at least in part, a rotatable disc of solid material allowing light to pass therethrough, said disc being substantially parallel to said surface, a motor within said casing and means associated therewith for rotating said disc, the face of said disc adjacent to said surface being uneven to provide irregular refraction and the opposite face being relatively smooth, and a multi-colored rotatable disc allowing light to pass therethrough interposed between said source of light and said first mentioned disc, said discs being in contact with each other.

OTTO JANZEN. 45
